UNITED STATES PATENT OFFICE.

LUDOVICO VAN VESTRANT, OF SOUTHALL, ENGLAND.

RETORT-CHARGING APPARATUS.

SPECIFICATION forming part of Letters Patent No. 450,688, dated April 21, 1891.

Application filed August 18, 1890. Serial No. 362,343. (No model.) Patented in England July 12, 1890, No. 10,831.

To all whom it may concern:

Be it known that I, LUDOVICO VAN VESTRANT, civil engineer, a subject of the Queen of Great Britain, residing at The Green, 5 Southall, in the county of Middlesex, in England, have invented a new and useful Improvement in Means and Apparatus for Charging Inclined Carbonizing-Retorts, (for which I have made application for a patent in Great 10 Britain, No. 10,831, bearing date July 12, 1890,) of which the following is a specification.

The object of this invention is to effect the charging of retorts for carbonizing with the 15 required amount of material in an even layer when the said retorts are built at an angle deviating from the horizontal and vertical line. I attain these objects by the mechanism illustrated in the accompanying drawings, in which—

Figure 1 is a vertical section showing the retorts *d* with the hopper *a* on the carriage *b* delivering the material down the flap *C* into the mouth of the lower retort. Hoppers 25 at various heights supported from above on rails *e e* or otherwise are described by dotted lines. Fig. 2 is a front elevation of the hopper and carriage. Fig. 3 is a side elevation.

My invention consists of a hopper *a*, constructed of any suitable material and of capacity equal to the total charge, this hopper to be in the form of a vertical tube, or the form being varied in width and length as may be necessary for the material and charge, 35 the bottom end or the whole of the hopper reduced to the width of the entrance to retort. I provide a falling bottom *k*, hinged at *l* and *l'*, or at back end, which fall is adjustable by suitable stops, (not shown,) which 40 can be raised or lengthened by levers (not shown) or the chains *j* over the pulleys *i*, as the angle of bottom is required to vary the velocity of the issuing material. On the bottom *k* being dropped, the front of hopper is 45 opened by the flap *c* falling forward to engage with the entrance of retort and forms a continuation of the bottom of the hopper and

delivers the material from the hopper to the retort as it escapes from the bottom of the hopper. The flap *c* and bottom *k* are closed 50 by the chains *j* and the rings *R* on the ends fastened on hooks *H* in the frame. (Indicated in Fig. 2.) The front of hopper has a slide *h*, which can be raised or lowered to control the rate of issue of material when 55 the front is dropped open. In Fig. 2 the mouth *m* is shown, through which the material passes out into the retort. The hopper is carried in or on a rectangular or other shaped frame *b*, which can run on wheels on 60 the floor or be suspended on wheels from above, as shown in Fig. 1, and guided therein by chains, links, or bars, so as to be lifted or lowered to the heights of the respective retorts, the said raising or lowering to be 65 performed by any of the usual means. The frame and hopper can be supported on a traveling frame on wheels above or below the front of the retort, so as to be movable from the supply of material to the mouth of 70 retort.

When it is desired to charge a retort, the frame containing the hopper is taken to the store-supply and filled with the requisite amount of material, from thence wheeled to 75 the front of retort after being adjusted to the desired height, so as to allow the requisite velocity of the issuing material to obtain even distribution over the floor or base of retort, and this can be varied to suit the varying 80 classes of material and the coefficient of friction due to the material, the floor of retort, and the inclination from the horizontal line of same by increasing or decreasing the angle of the bottom of hopper. The bottom *k* is 85 then lowered and the front delivery *C* opened and the issuing material allowed to gravitate into the retort, when the hopper is withdrawn, the retort closed, and the bottom *k* and flap *C* readjusted and the same operation repeated 90 on the next retort.

It will be understood that the foregoing is given by way of illustration only, and that the shapes, materials, and proportions of the

various parts may be varied in many ways within the scope of my invention.

What I claim, and desire to secure by Letters Patent of the United States, is—

- 5 A retort - charger comprising a wheeled frame, a hopper supported thereby and having an adjustable bottom, a flap pivoted to the bottom and adapted to fold over the front of the hopper when idle and to be used as a
10 chute when lowered, and a slide in the front

of the hopper to regulate the flow of material therefrom, substantially as set forth.

LUDOVICO VAN VESTRANT.
